HAIR REMOVER

Jacob M. Field, Brooklyn, N. Y.

Application October 25, 1948, Serial No. 56,409

12 Claims. (Cl. 51—186)

1

The subject matter of this invention is a functionally and structurally improved device particularly adapted to remove superfluous hair by applying and oscillating an exposed and fine abrasive sheet of a stack of such sheets along the skin surface of the user. The dominant object of the invention is realized in the provision of a pre-formed strap having means projectible through loose sheets of the stack and through a relatively resilient and flexible backing of such stack for effectively holding the latter in close superimposed relation against the backing. Specifically the invention has as a further object to arrange superimposed sheets of a stack in such manner that spaced slots thereof disposed along the side margins are in alignment with spaced gaps in the backing and to utilize connector means in the form of a preformed flexible and resilient strap having reduced parts constituting retaining loops for closely straddling the sides of the stack and backing and having means adapted to be threaded into the aligned slots and gaps for interlocking with the pad constituted by the stack and backing to preclude longitudinal and vertical displacement of the pad relative to the connector and having offset terminal means to retain the strap interlocked with the pad. The invention has as another important object to maintain the stack flatwise relative to the backing even though the stack is reduced to the last sheet thereof in the provision of compression means adapted to be held tightly against the several sheets due to the outward thrust applied to the reach of the strap when the palm of the user is interposed between the backing and the reach which is disposed at the rear surface of the backing. Other important objects and advantages will be hereinafter more particularly described in the following detailed specification considered in the light of the accompanying drawings wherein:

Fig. 1 is a perspective view of the hair remover illustrating the strap closed and holding the stack of sheets appropriately flatwise in respect to the backing.

Fig. 2 is a longitudinal sectional view taken along the line 2—2 of Fig. 1.

Fig. 3 is a view similar to Fig. 2 and showing the strap opened nevertheless maintaining the stack against the backing.

Fig. 4 is a fragmentary and broken rear view of Fig. 1 exhibiting one attenuated part of the strap threaded through the pad and with an offset terminal thereof held flatwise and against the backing by the reach of the flexible and resilient strap, and

2

Fig. 5 is a fragmentary elevational and front view of the hair remover.

Illustrative of the embodiment disclosed the hair remover according to my invention is broadly designated HR and is characterized by a pad P having a stack of superimposed and disassociated or disconnected sheets S and including a backing B to which these sheets are removably but closely held by the strap C.

More specifically each of the sheets S has a relatively fine abrasive coating A conveniently adapted to remove hair from the body of the user without injury to the skin and it will be observed that these sheets are provided with the aligned slots 10 and aligned slots 11 along vertical margins for registering with spaced but similar and aligned slots or gaps 12 and 13 interrupting the vertical or side margins of the backing B provided with a suitable outside felt coating F.

Since the flexible abrasive sheets S are disconnected and free of each other and of the rigid but flexible backing B, the strap C is utilized as a connector for holding these sheets in stack form flatwise and close together and to maintain the stack to the backing. To this end it is apparent that the strap C has a preformed bent shape and is preferably of a relatively thin flexible and resilient stock such as an appropriate plastic material having attenuated ends generally denoted E bent to define embracing portions or webs 14 which straddle the sides of the pad constituted by sheets S and the backing B. These embracing portions or webs 14 are preshaped to be substantially normal to the reach R of the strap C.

Compressive portions 15 inwardly overhang the embracing portions 14 and are integral therewith and approximately normal thereto and constitute a part of the ends E of the strap, serving to urge the stack of sheets against each other and against the backing. The reduced ends E of the strap further embody depending lips 16 threadable into and extend in part through aligned slots 10 and 12, and 11 and 13 of the stack and backing. These limbs 16 are disposed substantially parallel to the embracing portions or webs 14 and each integrally embodies an offset inwardly overhanging retaining lip L adapted to bear against the outside surface of the backing B and function as means to facilitate threading of the respective limbs into the aligned or registering slots as 10 and 12 or 11 and 13 of the stack and backing.

As illustrated the ends E of the preshaped strap C are reduced relative to the elongated reach R and after the strap is preformed to take the shape

substantially as that shown in Fig. 2, lips or terminals L are threaded through the alined slots of the pad and snap over the posterior face of the backing B. Thus loops LP straddle the side margins of the stack and backing and each of these may be said to characterize an embracing portion 14, a compression or gripping portion 15, and a limb 16 having an offset lip L. It follows that these loops lock the stack to the backing in a tight gripping relation.

Normally reach R is in close superimposed relation with the posterior but inwardly projecting retaining lips L (Fig. 2) which are offset or extend inwardly but laterally in respect to companion limbs 16. In such relation the strap is closed or collapsed although maintaining the stack closely against the backing by reason of the retaining loops LP which as previously stated removably interlock with the pad P.

In operation the user projects the palm of one hand between the reach R and the backing B. By such action the strap is opened or accurately flexed outwardly while the pad is also bowed outwardly but in an opposite direction (Fig. 4). Moreover the compressive or gripping portions 15 are also urged more tightly against spaced outer surface portions of the foremost sheet of the stack, thus firmly holding the sheets together and flatwise due to the outward thrust or tension on the reach R applied by the palm of the user.

With the hair remover mounted on the palm as above alluded to, an oscillating motion thereof against the skin removes superfluous hair on the local areas mechanically processed by the exposed abrading surface of the foremost sheet. Obviously after such processing and pursuant to the removal of the strap from the palm, the reach R due to its own resiliency snaps back to its flat relation against the backing (Fig. 2).

By the present invention although the several sheets of the stack are disassociated or disconnected from each other, each and every one thereof is maintained in a flatwise relation and after the foremost sheet has been torn off after use the remaining sheets of the stack are likewise held flatwise and close to the backing in processing of the skin in part due to outward thrust applied by the palm to the reach which is provided with rounded and relief portions 17 adjacent the reduced ends E. As an additional feature it is apparent that after all of the sheets of the stack is worn out, a new stack may be conveniently mounted on the backing by removing or detaching the strap and substituting a new unused stack followed by and again securing, that is, interlocking the strap with the new stack and original backing, as above explained.

Various changes may be made in details of construction and arrangement of parts without departing from the spirit of the invention or sacrificing any of the advantages thereof inherent therein.

I claim:

1. As a new article of manufacture for removing hair, a backing provided with spaced gaps, a stack of superimposed abrading sheets disconnected from each other and having registering and spaced slots in alinement with said gaps, a flexible and resilient strap comprising a reach movably disposed at the rear of said backing, and means to hold said stack to said backing and carried by said reach and in part straddling the sides of said stack and backing and in part interlocking with the walls of said slots and gaps

and embodying lip means interposed between said backing and reach.

2. As a new article of manufacture for removing hair, a relatively resilient and flexible backing provided with spaced gaps, a stack of closely superimposed abrading sheets disconnected from each other and having registering and spaced slots in alinement with said gaps, a flexible and resilient strap comprising an elongated reach movably disposed at the rear of said backing, and means to hold said stack to said backing and carried by said reach and in part straddling the sides of said stack and backing and in part interlocking with the walls of said slots and gaps and embodying lip means interposed between said backing and reach.

3. In combination, a backing provided with spaced gaps, a stack of sheets having registering and spaced slots in alinement with said gaps, and means for holding said stack to said backing comprising a strap having spaced retaining members straddling portions of said backing and stack and in part threaded into and through said slots and gaps and in part disposed against said backing.

4. In combination, a backing provided with spaced gaps, a stack of superimposed sheets having registering and spaced slots in alinement with said gaps, and means for removably holding said stack to said backing comprising a strap having spaced retaining loops straddling portions of said backing and stack and in part threaded into and through said slots and gaps and in part disposed against said backing.

5. In combination, a relatively rigid backing provided with spaced gaps along spaced side margins thereof, a stack of sheets having registering and spaced slots along side margins thereof and in alinement with said gaps, and means

40 for holding said stack to said backing comprising a flexible and resilient strap having spaced retaining loops straddling portions of said backing and stack and in part threaded into and through said slots and gaps and including offset terminal means in part disposed against said backing.

6. As a new article of manufacture, a backing provided with spaced gaps, a stack of sheets having registering and spaced slots in alinement with said gaps, a strap embodying a reach disposed at the rear of said backing and including ends comprising embracing portions straddling the sides of said backing and stack, compressive portions integral with said embracing portions for urging said stack against said backing, limbs integral with said embracing portions and offset relatively thereto and disposed within said slots and gaps, and lips integral with and offset relatively to said limbs and interposed between said backing and reach.

7. As a new article of manufacture, a relatively flexible backing provided with spaced gaps, a stack of superimposed sheets having registering and spaced slots in alinement with said gaps, a flexible and resilient strap embodying a reach disposed at the rear of said backing and including ends comprising embracing portions offset relatively thereto and straddling the sides of said backing and stack, compressive portions integral with and inwardly overhanging said embracing portions for urging said stack against said backing, limbs integral with said embracing portions and offset relatively thereto and disposed within said slots and gaps, and lips integral with and

offset relatively to said limbs and interposed between said backing and reach.

8. As a new article of manufacture for removing hair, a backing provided with spaced gaps, a stack of abrasive carrying sheets having registering and spaced slots in alinement with said gaps, a flexible and resilient strap embodying a reach disposed at the rear of said backing and including ends comprising embracing portions offset relatively thereto and straddling the sides of said backing and stack, compressive portions integral with and inwardly overhanging said embracing portions for urging said stack against said backing, limbs integral with said embracing portions and substantially normal thereto and removably disposed within said slots and gaps, and lips integral with and offset relatively to said limbs and interposed between said backing and reach.

9. As a new article of manufacture for removing hair, a backing provided with spaced gaps, a stack of abrasive carrying sheets having registering and spaced slots in alinement with said gaps, a flexible and resilient strap embodying a relatively elongated reach disposed at the rear of said backing and including reduced ends comprising embracing portions straddling the sides of said backing and stack, compressive portions integral with and inwardly overhanging said embracing portions for abutting said stack to urge the latter against said backing, depending limbs integral with said embracing portions offset relatively thereto and disposed within said slots and gaps, and terminal retaining lips integral with and offset relatively to said limbs and interposed between said backing and reach.

10. As a new article of manufacture for removing hair, a backing provided with spaced gaps, a stack of abrading sheets having registering and spaced slots in alinement with said gaps, a strap having a reach disposed in part at the rear of said backing, and loop means at the ends of said strap for straddling said stack and backing having means for holding said stack to said backing and including means removably insertable into said slots and gaps.

11. A flexible one piece strap for embracing and holding together a stack of sheets having spaced slots; comprising, a relatively wide reach adapted to be arranged at the rear of said stack, embrac-

ing portions extending downwardly and away from the ends of said reach for closely straddling the sides of said stack, compressive portions offset relative to and inwardly underhanging said embracing portions for engaging spaced side margins of the foremost sheet of said stack, limbs extending from said compressive portions towards said reach and offset relatively thereto and adapted to be threaded into said slots, and lips offset from said limbs and extending in a direction away from said embracing portions and adapted to be threaded into said slots in advance of said limbs for arranging thereof at the rear of said stack.

15 12. A flexible one piece strap for embracing and holding together a stack of sheets having spaced slots; comprising, a relatively wide reach adapted to be arranged at the rear of said stack, embracing portions extending downwardly and away from the ends of said reach for closely straddling the sides of said stack, compressive portions spaced from said reach and offset relative to and inwardly underhanging said embracing portions for engaging spaced side margins of the foremost sheet of said stack, limbs spaced from said embracing portions and extending from said compressive portions towards said reach and offset relatively thereto and adapted to be threaded into said slots, and lips offset from said limbs and extending in a direction away from said embracing portions and adapted to be threaded into said slots in advance of said limbs for arranging thereof at the rear of said stack.
